UNITED STATES PATENT OFFICE.

AMOS F. DIXON, OF NEWARK, NEW JERSEY, ASSIGNOR TO WESTERN ELECTRIC COMPANY, INCORPORATED, OF NEW YORK, N. Y., A CORPORATION OF NEW YORK.

SELECTIVE SYSTEM.

1,374,192.

Specification of Letters Patent. Patented Apr. 12, 1921.

Application filed July 2, 1917. Serial No. 178,225.

To all whom it may concern:

Be it known that I, AMOS F. DIXON, a citizen of the United States, residing at Newark, in the county of Essex and State 5 of New Jersey, have invented certain new and useful Improvements in Selective Systems, of which the following is a full, clear, concise, and exact description.

This invention relates to electromechanical selective systems, more particularly those 10 suitable for use in printing telegraphy.

On telegraph lines carrying considerable traffic, it is a common practice to supply duplex bridge apparatus. The maintenance 15 of this apparatus is at times troublesome, especially in the case of aerial lines where the insulation resistance of the line is variable, making it difficult at times to maintain satisfactory operation and it is often cheaper 20 to employ two separate line wires than to install and maintain the duplex bridge apparatus. Especially is this true in the case of lines connected to branch offices where the transmission lines are relatively short in 25 length.

It is the principal object of this invention to provide a system particularly suitable for two way working on short lines and one in which not only is the duplex balance 30 apparatus eliminated, but also one in which the simplified arrangement provides a further reduction in apparatus.

Another object is to provide a simplified system which does not require the use of 35 synchronizing apparatus at either station.

To accomplish these objects the invention contemplates at one of the stations, the use 40 of a constantly driven primary distributor adapted to operate with a current controller or automatic transmitter to place current impulses on the line, and with a receiving mechanism to distribute the impulses received over the line and record the character being selected. At the other station a secondary distributor is employed adapted to 45 coöperate with a transmitting mechanism and a receiving mechanism of a type similar to that used with the primary distributor. Electrically controlled means are also provided to restore the secondary distributor 50 to its normal condition at the end of each group of impulses. This secondary distributor is operated by impulses placed upon the line by the primary distributor and therefore no synchronizing apparatus is required to keep the two distributors in perfect step.

The several features of this invention may be more clearly understood by reference to the accompanying drawing which 60 discloses a specific embodiment particularly adapted for use in printing telegraphy. In the arrangement illustrated and described, the system is designed for operating by the well-known Baudot code of various combinations of five positive and negative impulses, but it will of course be understood 65 that other codes can be used equally well without in any way departing from the spirit of the invention.

70

Messages passing in one direction, such as from station A to station B, are always carried over one wire L^1 , and all messages passing in the opposite direction from station B to station A are carried over the other wire L^2 . At station A, which in the case of branch office working is preferably the central office station, are located the controller or transmitter 1 for selectively influencing 75 the flow of current over the line, the receiving apparatus 2 consisting of selecting magnets which on operation move a disk or perform some other function in connection with the recording of the character which is being selected, and the primary distributor, which in this case is shown as a rotary distributor 3, receives the outgoing impulses 80 from the transmitter and distributes them to the line and simultaneously receives and distributes to the various selecting magnets 85 the incoming impulses received from the line. The transmitter 1 which may be controlled by means of any convenient apparatus, such, for example, as character keys 90 arranged on the keyboard of a typewriter or an automatic mechanism controlled by a perforated tape or the like, consists of a plurality of pole-changers 4, 5, 6, 7 and 8, each of which has its movable contact member 95 permanently connected to one of the outer segments 9, 10, 11, 12 and 13, respectively, of the rotary distributor 3. These movable contact members are adapted to move independently of each other and when moved to the left engage fixed contacts 100 which are connected to the positive terminals of a source of current 14, the negative 105 terminal of which is grounded. When

moved to the right, these movable members engage another series of fixed contacts which are joined to the negative terminal of a source of current 15, the positive terminal of which is grounded.

The rotating arm 16 of distributor 3 is arranged to be driven constantly in a counter-clockwise direction by means of a motor or any similar mechanism (not shown). On the outer extremity of this arm is located an insulated section provided with a brush 17 connected to the line wire L¹ and adapted on rotation of the arm to wipe over and contact with the segments 9, 10, 11, 12 and 13 connected with the pole-changers as described above. On the face of the distributor and radially in line with the above mentioned segments are the inner segments 18, 19, 20, 21 and 22 which are permanently connected to the receiving magnets 23, 24, 25, 26 and 27, respectively. These inner segments are engaged by a brush 28 carried on another insulated section of the rotating arm 16. The inner portion of this arm is grounded and carries a brush adapted at the end of each revolution to make contact with the segment 29 which is permanently connected through the winding of relay 30 to a grounded source of current 31.

At station B there is provided a secondary distributor of the step-by-step type illustrated and described in detail in a co-pending application, Serial No. 869,333, filed October 29, 1914, together with transmitting and receiving mechanisms similar to those at station A. The sending and receiving sets of switches for this distributor comprise a plurality of contact springs 32, 33, 34, 35, 36, 37, 38, 39, 40 and 41, separated by suitable insulation and secured to any desired form of support. One spring of each of the sending switches 32, 33, 34, 35, 36 is connected to the movable contact member of the pole changers 42, 43, 44, 45, 46, respectively, the fixed contacts of these pole changers being connected to ground. The other springs of these switches are joined together electrically and connected to one of the line wires. One spring of each of the receiving switches 37 to 41, is connected to the front contact spring 47 of relay 48, while the other contact springs are connected to the selecting magnets 49, 50, 51, 52 and 53, respectively. These selecting magnets are arranged to move a disk or perform some other function in connection with recording the character being selected in the same manner as the selecting magnets 23 to 27, at station A.

The sending switches 32 to 36, inclusive, and the receiving switches 37 to 41, inclusive, are so arranged and coöperate with a suitable mechanism in such a manner that they are successively operated to produce

and distribute the effects of current impulses. This operation is brought about by means of an electromechanically operated member 54, provided with a plurality of pins 55, 56, 57, 58 and 59 which are adapted under certain conditions to close the corresponding pairs of switches 32, 37; 33, 38; 34, 39; 35, 40; and 36, 41, respectively. The actuating member 54 is pivotally carried by a spring-tensioned armature 60 of an electromagnet 61 and the downward motion thereof may be accelerated by means of a spring 62. The movements of the member 54 with respect to the sending and receiving switches is controlled by means of a step-like member 63, which is pivoted to a suitable frame, not shown in the drawing. A spring 64 secured to the member 63 and its supporting frame normally forces this member, if the electromagnet 61 is energized, against the stop 65. The actuating member 54 is provided with a downwardly extending portion 66, which is adapted to engage the different steps of member 63. A stop and elevating lever 67, pivotally supported in a suitable framework, also engages the steps of member 63 and coöperates with actuating member 54 for a purpose and in a manner to be presently explained.

The sets of switches 32 to 36, inclusive, and 37 to 41, inclusive, are arranged so that only one pair made up of one switch from each set is in the same horizontal plane, each succeeding set being lower than the one preceding by an amount sufficient to cause the corresponding pins 55 to 59, inclusive, to engage the proper pair of switches as the extension member 66 moves down the steps of member 63. In other words when member 66 rests on the upper step of member 63, as shown, only pins 55 can be active and engage the switches 32 and 37. When member 66 is moved down one step only pins 56 can engage their coöperating switches (33 and 38), while the remaining pins are either above or below their coöperating switches and are consequently inactive. On the next lower step, switches 34 and 39 may be acted upon by pins 57 and so on for the remaining pins and pairs of switches.

When the electromagnet 61, which controls the downward as well as the forward and backward movements of actuating member 54, is deenergized with the rest of the apparatus at normal, pins 55 engage and close the switches 32 and 37 while the extension member 66 rests upon the upper step of member 63 as shown. Upon the energization of electromagnet 61, switches 32 and 37 are opened and the movement of actuating bar 54 causes member 66 to drop off the upper step onto the next lower step of member 63.

When electromagnet 61 is again deener-

gized, the spring of its armature 60 retracts actuating member 54 and since the extension member 66 is on a lower step than before, pins 56 engage and close switches 33 and 38. After the first attraction of armature 60, upon each deenergization of electromagnet 61, the spring of armature 60, in moving the member 54 forward to close the proper switches, also causes the extension member 66 to move member 63 backward against the force of its spring 64 until the lever 67 drops down one step. Thereafter, upon the energization of electromagnet 61, the return movement of member 63 due to its spring 64, is arrested by the engagement of lever 67 and one of the steps. It will, therefore, be readily apparent that member 63 is moved step by step from its normal position upon each deenergization of electromagnet 61 and is held in its advanced position upon each energization thereof by lever 67. This change in movement continues for each energization and deenergization of electromagnet 61. It is therefore readily apparent that the successive actuation of the switches is due to a plurality of zig-zag movements of the actuating member 54, which movements being analyzed are resolved into backward, downward and forward components. In order to return the actuating member 54 to normal after each group of impulses, a restoring means is provided, consisting of an electromagnet 68 provided with a pivoted armature 69 normally held away from the core by gravity and the spring 70. Upon energization of electromagnet 68, the armature extension member 71 is elevated, causing the pins 72 and 73 to engage and raise the lever 67 and the actuating member 54, respectively, thereby freeing the member 63 and allowing it to be restored to its normal position against the stop 65 by the tension of the spring 64.

The energization of the electromagnet 61 is controlled either by relay 48 through its grounded armature 74 or by relay 75 through its grounded armature 76. The windings of these relays are connected in parallel between one side of the line and ground. Relay 48 is polarized to respond only to current impulses of positive polarity, whereas relay 75 responds only to current impulses of negative polarity.

Relay 48 is provided with a second armature 77 connected to a grounded source of energy 78. The front contacts of armature 74 of relay 48, and armature 76 of relay 75 are connected through the windings of electromagnet 61 to a grounded source of energy 79 and a restoring circuit now to be described.

In order to return the apparatus to normal at the end of each succession of impulses, pins 59, in addition to closing switches 36 and 41, are also arranged to

close a switch 80, the contact spring of this switch being connected to the front contact of armature 74, while the other is connected to a grounded source of energy 81 through the winding and the movable contact 82 of 70 the restoring relay 83. This relay is provided with a pair of armatures 84 and 85 joined together electrically and connected to ground through the back contact of armature 86 of the clearing-out relay 87. One 75 terminal of the winding of relay 87 is connected to a grounded source of current 88, the other terminal being connected to the back contact 89 of a switch operated by the movement of armature 69 of electromagnet 80 84, and having its movable member 90 grounded. The front contact of armature 84 of relay 83 is connected through the windings of electromagnets 68 and 61 in series to the grounded source of current 79. 85

A better understanding of the system may be obtained by following the successive operations taking place during the transmission and receiving of current impulses representing the various characters. To do this, let it be assumed that the system is in operation and station A is about to send the character D over the line to station B. The letter D in the Baudot code consists of five current impulses arranged in the following 95 order: positive, negative, negative, positive, negative. The transmitter 1 at station A is therefore operated so that the movable contacts of pole changers 4 and 7 engage the fixed contacts at the left, which are connected to the positive terminal of a grounded battery 14, whereas the movable contacts of pole changers 5, 6 and 8 engage the fixed contacts at the right which are connected to the negative terminal of the grounded battery 15. The operation of these pole changers may be brought about by various means, such for example, as the operation of a character key on an ordinary typewriter keyboard or by the use of a perforated tape. 110 With the transmitter operated as described, the segments 9 and 12 of rotary distributor 3 are connected to positive battery and segments 10, 11 and 13 are connected to a battery of negative polarity. As the arm 16 rotates in a counter-clockwise direction, the outer brush 17 will contact with segment 9, thereby completing a circuit from grounded battery 14 through pole-changer 4, segment 9, brush 17, line wire L² and the windings of 120 relays 48 and 75 connected in parallel to ground. The relay 75 being polarized to respond only to negative impulses will not be affected, but relay 48 which responds to positive impulses will be energized, causing 125 the attraction of its armature 74 and 77. The operation of armature 77 provides a path for current flow from the grounded source of energy 78 through the contacts of switch 37 and the selecting magnet 49, there- 130

2
by permitting the latter to perform its function in connection with the recording of the character being selected. As armature 74 engages its contact, a circuit is provided from the grounded source of energy 79 through the winding of electromagnet 61 and armature 74 to ground. Electromagnet 61 thereupon attracts its armature 60 to which is pivoted the actuating bar 54 and causes the opening of both switches 32 and 37. Further movement of the bar 54 allows the extended portion 66 to drop down on the next lower step of member 63.

As the brush 17 leaves segment 9 of rotary distributor 3, the relay 48 is deenergized, allowing its armature to fall back and in so doing cause the deenergization of electromagnet 61. The armature 60 is then drawn back by its spring and since member 66 is on a lower step than before, pins 56 engage and close switches 33 and 38.

The next operation takes place when brush 17 engages the segment 10 of rotary distributor 3. A circuit is then completed from the grounded source of energy 15 through pole-changer 5, segment 10, brush 17, line wire L¹ and the windings of relays 48 and 75 in parallel to ground. Since relay 48 responds only to currents of positive polarity, it will not be affected in the present case and no circuit will therefore be provided through the selector magnet 50. However, relay 75, which is responsive to currents of negative polarity, will be energized attracting its armature 76 and thereby providing a path to ground for the source of energy 79 through the winding of electromagnet 61. The attraction of armature 60 allows the member 66 to drop down another step on the member 63 and also to open the switches 33 and 38. As the brush 17 leaves segment 10, relay 75 is deenergized, in turn deenergizing electromagnet 61, allowing the armature 60 to be retracted and thereby causing the closure of switches 34 and 39 by the pins 57. The operation of the apparatus upon the third impulse which is transmitted when the brush 17 wipes over segment 11 is the same as that for the second impulse just described. The extended portion 66 of actuating bar 54 is dropped down another step on member 63 and at the end of the operation, switches 35 and 40 are closed by the pins 58. The selecting magnet 51 remains unoperated.

As the brush 17 contacts with segment 12, current of positive polarity flows over the line, operating the relay 48 and attracting its armatures 74 and 77. The attraction of armature 77 closes the circuit from the grounded source of energy 78 through armature 77, switch 40, and selecting magnet 52, causing the latter to operate and perform its function in recording the character. By 65 the attraction of armature 74, the electro-

magnet 61 is again energized due to the flow of current from the grounded source of energy 79 through the winding of electromagnet 61 and armature 74 to ground. The attraction of armature 60 causes the movement of actuating bar 54 and results in the opening of switches 35 and 40. A further movement of this bar allows the extended portion 66 to drop on the next lower step of member 63 so that upon deenergization 75 of electromagnet 61, the pins 59 are in engagement with switches 36, 41 and 80. The last impulse of the group set up on the transmitter 1 is sent over the line when brush 17 engages segment 13. In this case, 80 the source of energy 15 of negative polarity causes the energization of polarized relay 75. The operation of this relay again energizes electromagnet 61, due to the flow of current from the source of energy 79 through 85 the winding of 61 and armature 76 to ground. The operation of electromagnet 61 causes the attraction of armature 60, drawing back the actuating bar 54 and opening the switches 36, 41 and 80. As a result of 90 this impulse, the selecting magnet 53 is not operated during this impulse.

Upon the operation of relay 75, a circuit to ground is also completed from the source of energy 81 through the winding of relay 95 83, movable contact 82, switch 80 and armature 76. Upon the energization of relay 83, its armature 85 is attracted, causing it to engage the movable contact 82 and open the circuit to the switch 80. At the same time, 100 however, a holding circuit is provided for the relay 83 from source of current 81 through relay 83, movable contact 82, armature 85 of relay 83 and armature 86 of clearing-out relay 87 and to ground. This holding circuit makes the restoring of the apparatus positive and independent of the length of time during which switch 80 remains closed.

As the brush 17 leaves segment 13, relay 10 75 is deenergized. However, relay 83 remains operated, providing a path for current flow from source of energy 79, through the windings of electromagnets 61 and 68 in series, armature 84 of relay 83 and armature 115 86 of relay 87 to ground. The armature of electromagnet 68 is attracted and causes the return of the actuating bar 54 and step member 63 to their initial positions. The operation of armature 69 also causes the movable 120 contact 90 to engage with the fixed contact 89, thereby providing a path to ground from the source of energy 88 through the winding of relay 87. Upon the energization of relay 87, armature 86 is attracted, opening 125 the holding circuit through relay 83 and thereby causing the restoring apparatus to return to its normal condition.

As the distributor arm 16 continues in its rotation, the grounded brush 91, wipes over 130

segment 29, providing a path to ground from the source of energy 31 through the winding of magnet 30, segment 29 and brush 91. The operation of this magnet may be utilized for feeding the tape when an automatic system is used or stepping ahead the mechanism when operating manually.

In following the operation of this system in transmitting current impulses from station B to station A, let it be assumed that the transmitter at station B has been operated to transmit the letter D, which as previously stated consists in the Baudot code of a succession of five current impulses arranged as regards polarity in the following order: positive, negative, negative, positive, negative. The setting of the transmitter to give this arrangement of impulses, may be obtained by any of the well-known means as, for example, the operation of a character key on an ordinary typewriter keyboard, or by means of a perforated tape working in conjunction with an automatic sending mechanism. To transmit the desired series of impulses, the movable contacts of pole-changers 42 and 45 are displaced to the left, engaging fixed contacts which are connected to ground. The movable contacts of pole-changers 43, 44 and 46 will remain unoperated.

It has already been pointed out that in the normal position of the distributor at station B, the switches 32 and 37 are engaged by the pins 55, therefore, with the movable contact of pole-changer 42 engaging its grounded contact, a path is provided for current flow from the grounded source of energy 92, located at station A, through the winding of relay 93 and over the line wire L² to switch 32 and thence to ground through pole-changer 42. The energization of relay 93 causes its armature 94 to be attracted, thereby connecting the grounded source of energy 95 to the brush 28 of distributor arm 16. As this arm wipes over segment 18, which is in line radially with segment 9, a path to ground is provided through the selecting magnet 23, thereby operating this magnet and allowing it to perform its function in recording the character being received. Since the manner in which switches 32 to 36 are operated has already been described in detail, it will be understood that these switches will be closed in order, as the distributor arm 55 wipes over segments 10 and 19, 11 and 20, 12 and 21, 13 and 22. During the second and third sending intervals, switches 33 and 34 respectively, are closed, but since the movable contacts of pole-changers 43 and 44 do not engage the grounded contacts, relay 93 is not energized and the selecting magnets 24 and 25 accordingly remain unoperated. Upon closing of switch 35 relay 93 is energized by the flow of current passing through its winding from the source of

energy 92 to switch 35 and pole-changer 45 to ground. As the brush 28 now engaged segment 21, current flows from the source of energy 95 through armature 94, brush 28, segment 21 and selecting magnet 26, causing the latter to operate and perform its function in recording the character. During the fifth sending interval, switch 36 is closed, but since the energizing circuit of relay 93 is open at pole-changer 46, no impulse is transmitted to operate the selecting magnet 27. The manner in which the step-by-step distributor at station B is restored to normal after receiving the group of five current impulses, has already been explained and will not be repeated here. The operation of relay 83 in addition to performing its function in restoring the distributing mechanism to normal condition also provides a path of current flow from the grounded source of energy 96, through magnet 97, and armature 98 of relay 83 to ground. The operation of this magnet which it will be noted occurs after the sending of each group of impulses may be used for feeding the perforated tape when using an automatic transmitter or for performing some similar operation when the sending is done manually.

For the sake of clearness, connections are shown in the drawing as being made directly to the brushes 17 and 28 of rotary distributor 3. It will, of course, be understood that in practice, these connections are made permanently to slip rings, the brushes of which would in turn be joined electrically to brushes 17 and 28.

It may be found that under certain conditions the relay 93 can be dispensed with, in which case, the source of energy 95 is connected directly between brush 28 and the line wire L².

What is claimed is:

1. In a selecting system, a plurality of stations, a pair of line conductors connecting said stations, an impulse transmitting mechanism at each station comprising a group of selectively operated contacts, a selecting mechanism at each station comprising a group of magnets selectively operated in accordance with impulses transmitted over a line conductor by the transmitting mechanism at another station, and a distributor at each station operable to connect the transmitting mechanism at that station with one of said line conductors and to connect the selecting mechanism at that station with the other of said line conductors, one of said distributors including means for impressing current impulses upon the line circuit for operating said other distributor in unison therewith.

2. In a selecting system, a plurality of stations interconnected by a pair of line wires, transmitting and receiving mecha-

nisms at each station, a primary distributor at one of said stations for connecting the transmitting mechanism at that station with one of said line wires and the receiving mechanism with the other of said line wires, a secondary distributor at a second station for connecting the transmitting mechanism at that station with the line wire with which the receiving mechanism at said first station is connected and connecting the receiving mechanism at that station with the other of said line wires, and means responsive to impulses impressed upon one of said line wires by said primary distributor to drive 15 said secondary distributor in unison therewith.

3. In a selecting system, a plurality of stations, a pair of line wires extending between the stations, transmitting and selecting mechanisms at each station, a distributor at each station, means forming a part of one distributor for associating the transmitting mechanism located at that station with one of the line wires for the purpose of impressing current impulses upon such line wire, means at the other station responsive to such impulses for driving the distributor at the second station in unison with said first distributor and means included in said second distributor for associating said line wire

10 15 20 25 30

with the selecting mechanism at the second station and for associating the transmitting mechanism at such station with the other line wire for the purpose of impressing current impulses upon the other line wire to 35 operate the selecting mechanism at said first station.

4. In a selecting system, a primary and a secondary station, a pair of line wires connecting said stations, transmitting and receiving apparatus at each of said stations, a constantly driven distributor at said primary station for connecting said transmitting apparatus thereto to one of said line wires, and said receiving apparatus to said 40 other line wire, a step-by-step distributor at said secondary station, means responsive to impulses received from said primary station for driving said step-by-step distributor, selecting means at said secondary station 50 under the control of said step-by-step distributor and selectively responsive to said impulses, and transmitting means under the control of said step-by-step distributor for sending selecting impulses to said primary 55 station over said other line wire.

In witness whereof, I hereunto subscribe my name this 29th day of June, A. D. 1917.

AMOS F. DIXON.
